UNITED STATES PATENT OFFICE

JOSEPH JEAN MARIE GUEUX, OF IVRY-SUR-SEINE, FRANCE

ELECTRICAL CONTROLLING DEVICE FOR LIQUID DISTRIBUTORS

Application filed November 12, 1931, Serial No. 574,635, and in France November 12, 1930.

The present invention relates to an electric operating device for automatic distributors of liquid whose operation is automatically effected when the feed pump of said distributor is itself operated. The device in conformity to the present invention thus relates to the operation of the said pump.

In conformity to the invention, in the main upright support of the apparatus is mounted a casing of an absolutely leakless nature containing an electric motor adapted to drive a speed-reducing device whose driven shaft extends through the said casing through a leakless bearing.

When the pump operates by reciprocating motion, on the driven shaft of the speed-reducing device is mounted a crank disc to which is pivoted a connecting rod whose other end is pivoted to a driving crank disc loosely mounted on the pump shaft.

The said driving crank disc is provided with tenons which are normally in engagement with corresponding recesses in a wheel keyed to the pump shaft.

A nut or like member is provided in order to maintain the disc against the wheel, in such manner that by simply loosening the nut, the disc can be disengaged, and the pump may now be operated by hand if desired.

When the pump is of the rotary type, two sprocket-wheels carrying a driving chain are keyed respectively to the pump shaft and to the driven shaft of the speed-reducing device.

However, the pinion mounted on the shaft of the speed-reducing device is provided with a loose wheel ratchet device in such manner as to rotate in a certain direction with reference to the secondary shaft of the speed-reducing device, this latter being in most cases of the irreversible type.

To allow the pump to be operated by hand if desired, the apparatus comprises a double intermediate sprocket-wheel carrying two respective driving chains whereof one leads from the sprocket-wheel provided with the said loose wheel device and the other leads to the sprocket-wheel, mounted on the pump shaft. The shaft of this intermediate sprocket-wheel may receive a hand-crank.

The motor drives an air fan adapted to ex-

pel to the exterior of the air contained in the motor casing.

The electric circuit for the motor comprises a switch which is preferably of the rocking mercury-tube type and is controlled by an operating or engaging knob which is brought back to the releasing position when the proper amount of liquid has been delivered. To this knob is added a releasing button which serves in case of accident to at once break the motor circuit and to thus stop the delivery of fuel.

According to one form of construction, the engaging knob acts by an arm upon a small weighted lever secured to the rocking device; said lever is held in place by another weighted lever which may be acted upon by the releasing button and may also be acted upon by a stop provided upon a suitable movable part of the mechanism of the distributor and so arranged that the said stop may act upon the weighted lever when the predetermined amount of the liquid has been delivered.

In the major part of the known distributors, the amount of liquid to be delivered is determined in advance by turning by hand a disc bearing the indications for the various quantities. After the apparatus has been started, this disc returns to the original position according as the feeding takes place. Hence the stop above mentioned will be preferably actuated by such a disc when the latter returns to its initial position.

A constructional form of the electric driving device in conformity to the invention is shown by way of example in the accompanying drawings.

Fig. 1 is a sectional elevational view of the main upright support of the apparatus used for the delivery of liquids.

Fig. 2 is a view, on a larger scale, of the means connecting the pump with the operating rod.

Figs. 3 and 4 show the internal arrangement of the electric switch provided with the said rocking device.

Fig. 5 is a section on the line V—V of Fig. 2.

Figs. 6 and 7 relate to a modified form of

construction of the means connecting the speed-reducer with the pump.

In Fig. 1, 10 is the main upright which supports the distributor and contains the 5 feed pump 11 of the distributor whose delivery pipe is shown at 12; at 13 is a safety by-pass, and at 14 the suction pipe on which is a filter 15.

In the known manner, the shaft 16 of the 10 pump carries a wheel 17 engaging a like wheel 18 mounted on the main frame and actuating an eccentric 19 to which is pivoted a rod 20 adapted to control the mechanism of the distributor in any suitable manner.

15 Thus by turning the shaft 16 alternately in one and the other direction in such manner as to act upon the pump 11, this actuates at the same time the eccentric 19 and imparts a reciprocating motion to the rod 20, this motion being utilized by the mechanism of the distributor to effect all the movements required for the delivery of liquid.

In conformity to the invention, an absolutely leakless case 21 is situated in the main 25 support 10 of the distributor, and it contains an electric motor 22 which actuates (through a coupling 23) a speed-reducer 24 whose driven shaft 25 traverses the case 21 through an absolutely non-leaking stuffing-box 26.

30 The shaft 25 carries, at the exterior of the case 21, a crank 27 to which is pivoted a connecting rod 28 which is attached at the other end to the periphery of a disc 29 (Figs. 1 and 2) which is loose on the hub of the gear 35 wheel 17.

The gear wheel 17 has on its outer face two trapezoidal recesses 61 adapted for the engagement of two respective tenons 62 of like form, secured to the disc 29 under the action 40 of a nut 31 (Figs. 2 and 5). In this manner the wheel 17 can be actuated by the disc 29. A centering arm 30 provided in one of the tenons 62 of the disc 29 serves to readily determine, when assembling the device, the 45 exact position of the corresponding recess 61.

On the end of the shaft of the electric motor is mounted an air fan 32 rotatable in an annular chamber 33 situated in the case 50 21, and to the center of the chamber is connected a pipe 34 leading to the exterior of the distributor. A second pipe 35 leads from the exterior of the distributor to any suitable point of the case 21.

55 The operation of the apparatus is as follows.

When the electric motor 22 rotates, the small fan 32 produces a suction in the case 21, and thus fresh air will enter through the 60 pipe 35. The said fan also expels air from the case, through the pipe 34. In this manner, the case is not only quite leakless by its construction, but on the other hand the vapors which might enter the said case will be at 65 once expelled by the aerating action of the

fan 32. In this manner, no risk is to be apprehended.

In order to avoid all opening of the case 21, while being enabled to lubricate the rotating parts, each point to be lubricated is 70 provided with a small pipe such as 36, which leads to an external oiling tube 37 suitably situated.

The rotation of the electric motor 22 effects the rotation, at reduced speed, of the crank 75 27, so that the connecting rod 28 will be moved, thus causing an alternate pivoting motion of the disc 29. As this latter is held fast by the nut 31, on the wheel 17, which is secured to the pump shaft, the pump and 80 the distributor will operate in the same conditions as if the pump were operated by hand.

In case of damage to the electric motor or to the driving parts, the shaft 16 of the 85 pump can be driven by means of a socket wrench engaged upon the square end of said shaft. However, it is necessary to loosen the nut 31 in order to separate the disc 29 from the wheel 17, and thus release the two 90 tenons 62 and the arm 30 from the recesses 61 of the wheel 17. If this precaution were not taken, it would be impossible to act upon the pump shaft 16, for as a general rule the speed reducer is non-reversible and can be 95 given no other motion than the one it receives from the motor.

To again start the motor, the operator turns the gear wheel 17 while tightening the nut 31, so that the arm 30, urged by its 100 spring, will engage in the corresponding recess 61 of the wheel 17, and in this event the tenons 62 are exactly in coincidence with the recesses 61, and it is simply necessary to screw the nut clear down.

The motor is supplied by an electric circuit consisting of conductors 38 contained in a leakless tube 39, and leading to a junction box 40, a switch 41 being provided for starting and stopping the motor.

Figs. 3 and 4 show in detail the arrangement of the said switch.

It essentially comprises a tilting mercury-tube device 42, known per se, which is supplied by the electric conductors 38 and is 115 adapted to pivot about an axle 43, it being secured to an arm 44 carrying a weight 45. The said arm cooperates with a catch 46 which is controlled from the exterior by a 120 knob 47.

The arm 44 acts in such manner that the normal position of the rocking device 42 is the one in which the electric circuit is broken. The arm 44 carries a stud or stop 48 cooperating with an appendage or arm of a pivoting 125 lever 50 which carries a weight 51 and may be acted upon by a tapered part provided upon a push-button device 53. (Fig. 4).

The form of the lever 50 is such that when pressing upon the button 53 and thus pivot- 130

ing the lever, the appendage 49 will be separated from the stop 48, and the rocking device will turn by the action of its weight.

On the lever 5 is mounted a stud 54 engaging a hook 55 formed on the end of a rod which is pivoted to a pivoting lever 57 which may be acted upon at the end of the movement by a tappet 58 provided upon the distributor dial 59. This dial is of the same kind as is provided upon all automatic distributors and permits to preliminarily determine the quality of liquid to be delivered by the apparatus.

The operation of the aforesaid device is as follows.

When it is desired to start the distributor, the operator turns the dial 59 until the figure corresponding to the quantity of liquid to be supplied appears in an opening 60 of the main support. He then turns the knob 47 so that the rocking device 42 will pivot about and will thus bring the stud or stop 48 against the arm 49 of the lever 50. The circuit of the motor is thus closed, and the motor starts in operation.

When the supply of the liquid is nearly finished, the dial 59 has returned to its original position, and the stud 58 tips up the lever 57 and raises the link 56; the arm 54 is also raised, the lever 50 turns about, and its arm 49 escapes from the stop 48.

The rocking device, which is turned about by its weight 45, resumes its normal position in which the electric circuit is broken.

If it is desired to stop the electric motor by hand at any time, the operator pushes the button 53, whose tapered part 52 causes the lever 50 to turn in the same conditions as before.

In the modified construction shown in Figs. 6 and 7, 70 is the main frame or support of the distributor supplying the liquid, and upon the said support is mounted a pump 71 whose shaft 72 operates in a bearing 73. The suction and discharge conduits of the pump 71 are shown respectively at 74 and 75; this pump is of the rotary type, and thus when in operation the shaft 72 must rotate in a given direction. The said shaft carries an eccentric 76 adapted to drive—through the medium of the rod 20—the controlling mechanism of the distributor itself.

On the other hand, the pump 71 is driven by the electric motor 22 which is directly coupled at 23 to the driving shaft of the speed reducer 24 whose driven shaft is indicated at 25.

The parts are mounted in such manner that the shaft 25 of the speed reducer is parallel with the shaft 72 of the pump 71.

To the shaft 72 of the pump 71 is keyed a sprocket wheel 77 actuated by a chain 78 engaged with one set of teeth of the double sprocket wheel 79. The other set of teeth of this double wheel engaged a second chain 80

co-operating with a sprocket wheel 81 mounted on the shaft 25 of the speed-reducer 24 through the medium of a loose wheel device 85. (Fig. 7.)

The double wheel 79 is mounted on a shaft 82 supported by the main frame 70 of the apparatus; one end 84 of the shaft 82 extends to the outside of the said frame, it being protected by a removable cap 83. This end 84 of the shaft 82 has a square or like form, adapted for engagement with an operating handle, not shown.

The operation of the modified apparatus shown in Figs. 6 and 7 is as follows.

During the normal functioning of the apparatus, with the motor in operation, the motor drives the shaft 25 at reduced speed, and also drives the double sprocket wheel 79 by means of the chain 80; said wheel drives the sprocket wheel 77 and also the shaft 72 of the pump 71 by means of the chain 78, and thus the pump will be operated, and the mechanism of the distributor will be driven by the rod 20.

If the motor 22 or the speed-reducer 24 are put out of use by accident, and if it is still desired to make use of the distributor, the operator removes the cap 83 and mounts a handle upon the end 84 of the shaft 82. This shaft, and hence the sprocket wheel 79, are thus driven in the proper direction, and this will also rotate the shaft 72 of the pump 71, as before.

On the other hand, this rotation is not hindered by the presence of the speed-reducer 24, which is usually non-reversible, as the lower sprocket wheel 81 will rotate with reference to the shaft 25 of the said speed-reducer, due to the ratchet arrangement of the loose wheel 85.

It is thus observed that in order to change over from motor operating to hand operating, it is not necessary to remove any of the parts, nor to perform any additional operations.

In the manufacture of the apparatus, care has been taken to use diameters for the sprocket wheels 77 and 79 such that the pump shaft will be driven at the most suitable speed, both for the motor drive and for the operating by the handle. As a general rule, the ratio between the speed of the pump shaft and the speed of the motor shaft is approximately 1:3.

I claim:

1. An electric operating device for automatic liquid distributors comprising a pump, an electric motor for controlling said pump, a speed reducer between said motor and pump, and a leakproof casing enclosing said electric motor and speed reducer, and mounted within the body of the distributor.

2. An electric operating device for automatic liquid distributors comprising a pump, an electric motor for controlling said pump,

a leakproof casing enclosing said motor and mounted within the body of the distributor, a ventilator disposed inside of said casing and actuated by the motor, and air circulating means cooperatively associated with said ventilator.

3. An electric operating device for automatic liquid distributors comprising in combination with the main upright of the distributor, a leakproof casing mounted in said upright, an electric motor and a speed reducer enclosed within said casing, a shaft

driven by said speed reducer and extending outwardly of the casing, a crank connected to said shaft, a pump having a driving shaft, a disk freely mounted on said pump driving shaft and connected to the crank, a wheel 70 fixed to the pump driving shaft and having means effecting a sliding engagement with said disk, and means holding the disk against the wheel for maintaining their inner engagement.
